UNITED STATES PATENT OFFICE.

SAMUEL ROBERT SCHWARTZ AND AUGUST BOSTROEM, OF NEW YORK, N. Y.,
ASSIGNORS TO SAID SCHWARTZ.

DESIGN FOR A LAMP-SHADE.

59,788.

Specification for Design.

Patented Nov. 22, 1921.

Application filed February 11, 1921. Serial No. 444,303. Term of patent 14 years.

To all whom it may concern:

Be it known that we, (1) SAMUEL ROBERT SCHWARTZ and (2) AUGUST BOSTROEM, citizens of the United States of America, residing at (1) New York, in the county of New York and State of New York, and (2) New York, in the county of Bronx and State of New York, have invented a new, original, and ornamental Design for Lamp-Shades, of which the following is a specification, reference being had to the accompanying drawings, forming part thereof.

Figure 1 is a perspective view of our lamp shade,

Fig. 2 is a view of one end of the same,
Fig. 3 is a front elevation of the same, and
Fig. 4 is a plan view of the said shade.

A very characteristic feature of our design is that constituted by the chamfer or bevel provided where the ends of the shade join the connecting curved surface.

We claim:

The ornamental design for a lamp shade, substantially as shown.

In testimony whereof, we have signed our names to this specification in the presence of two subscribing witnesses, this ninth day of February 1921.

S. ROBERT SCHWARTZ.
AUGUST BOSTROEM.

Witnesses:

I. SMITH,
S. ABRAMS.
